UNITED STATES PATENT OFFICE

WILLIAM W. CARSON, JR., OF KNOXVILLE, TENNESSEE, ASSIGNOR, BY MESNE ASSIGNMENTS, TO THE FULTON SYLPHON COMPANY, OF KNOXVILLE, TENNESSEE, A CORPORATION OF DELAWARE

THERMOSTATICALLY-CONTROLLED VALVE MECHANISM

Application filed October 30, 1926. Serial No. 145,344.

This invention relates to thermostatically controlled valve mechanism, and particularly to valve mechanism of this character for controlling the circulation of cooling medium through the cooling systems of internal combustion engines. The invention is capable of embodiment both in thermostatically controlled valve mechanism of the choker type wherein the opening and closing of the valve determines the quantity of cooling medium flowing through the system and in thermostatically controlled valve mechanism of the by-pass type wherein the opening and closing of the valve determines the path of flow of the cooling medium.

It is an object of this invention to provide a device of the character described which is simple in construction, inexpensive to manufacture and install, and accurate and efficient in operation.

Another object of this invention is to provide a device of the character described with simplified means for supporting and enclosing the thermostat; also to simplify the construction both as respects the provision of a valve seat and the provision of a means for mounting the entire unit in operative relation to the cooling system of an internal combustion engine.

Other objects will appear as the description of the invention proceeds.

The invention is capable of receiving a variety of mechanical expressions, two of which are shown on the accompanying drawings, but it is to be expressly understood that the drawings are for purposes of illustration only and are not to be construed as a definition of the limits of the invention, reference being had to the appended claims for that purpose.

Referring in detail to the drawings, wherein the same reference characters are employed to designate corresponding parts of the several figures,

Fig. 1 is an enlarged axial section through a thermostatically operated valve mechanism embodying the present invention.

Fig. 2 is a section on the line 2—2 of Fig. 1.

Fig. 3 is a perspective view of the cup-like cage constituting a part of the unit of Fig. 1.

Fig. 4 is an enlarged axial section through

a second embodiment of the present invention, and

Fig. 5 is a perspective view of the cup-like cage which forms a part of the unit of the embodiment of Fig. 4.

In the form shown in Figs. 1, 2 and 3, a thermostat 1 of any suitable character and possessed of any suitable physical characteristics is shown as composed of a deeply corrugated, highly flexible, expansible and collapsible tubular metal wall, preferably of resilient metal, said tubular wall being closed at one end by an end wall 2, designed to be maintained stationary, and closed at its opposite end by an end wall 3 designed to be movable, said end walls being attached to the corrugated lateral wall in any suitable way, as by brazing or soldering.

On the thermostat, mounted on the end wall 2, and preferably integral therewith, is an axially extending boss 4 threaded exteriorly and designed to receive a nut 5 for the purpose of mounting the thermostat in fixed position as hereafter explained. The usual filling aperture 6 for said thermostat may be provided through said boss 4, if desired, said filling aperture being shown as closed by a stopper 7 and solder 8 after a thermosensitive fluid of any suitable character has been introduced into the thermostat.

The opposite end wall 3 of said thermostat is provided in any suitable way with a valve stem 9, integral therewith or suitably attached thereto, and shown as exteriorly threaded at its outer end 10. Interiorly of the thermostat, said end wall 3 is shown as provided with a tubular stop 11, integral therewith or suitably attached thereto as by solder, for limiting the extent to which the thermostat may be collapsed when the valve member is not in operative position.

In conformity with the present invention said thermostat is supported in fixed position and also enclosed by a cup-shaped cage 12 provided with a bottom 13, which may be integral with the lateral wall or suitably attached thereto as by solder, said bottom wall being provided with a central aperture 14 through which the boss 4 of the thermostat may be projected so as to permit the sta

tionary end wall 2 of the thermostat to be fixedly clamped to the bottom of said cup-shaped cage or support by threading the nut 5 onto the boss 4. To permit free circulation of the cooling medium into the cage, over and around the thermostat, the lateral or cylindrical wall of said cage is provided with a suitable number of suitably sized apertures, said apertures being separated by a plurality of longitudinally extending ribs 15 of any suitable shape and size to give the desired rigidity and stiffness to the cage without unduly restricting the circulation. At least one pair of opposed ribs 15 is preferably decreased in width adjacent the end thereof near the open end of the cup-shaped cage, as shown at 16 and each reduced portion 16 is connected to the main portion of the rib 15 at each side of the rib by a beveled surface 17 for a purpose hereinafter explained. For convenience in assembling all of the ribs 15 are preferably made of identical construction.

The open end of the cup-shaped cage 12 is provided with a radially extending flange 18, which flange is preferably integral with the lateral or cylindrical wall of the cup-shaped cage and may project either radially inward or radially outward. In the form shown in Figs. 1 and 3 said flange 18 is shown as extending radially outward. The outer face 19 of said flange 18 is preferably machined or otherwise suitably formed to constitute a valve seat for the valve to be described.

Means are provided on said cup-shaped support or cage for mounting the thermostatically operated valve unit in operative position in relation to the parts of the cooling system of an internal combustion engine, and to this end an annular flange 20, which may be blanked out of sheet metal, has an inside diameter of sufficient size to fit snugly over the exterior periphery of the cup-shaped support 12 and an outside diameter and configuration appropriate for assembly with the parts by which the unit is to be mounted.

Means are also provided for clamping this annular flange 20 in position against the inside of the flange 19, and this clamping means is preferably so constructed as to also perform the function of guiding the valve stem 9 and, if desired, limiting the expansive movement of the thermostat 1. In the form shown (see particularly Fig. 2) said clamping means is composed of a pair of elongated metal strips 21 and 22, preferably blanked out of sheet metal and each provided intermediate its length with a bend 23 of substantially semi-circular configuration. Adjacent their opposite ends, each of said metal strips is provided with a generally right angular bend 24 and the ends of the deflected portions are reversely bent as shown at 25 to afford hook-like extremities. Two

metal strips bent in the manner described, or into any other suitable conformation to perform the function to be described, are assembled, so that their faces contact in a plane 26, to embrace the valve stem. The two members 21 and 22 are then secured together in this position in any suitable way, as by screws or rivets 27, passed through aligned apertures therein. When so assembled the pair of hooks 25 at each end of the transverse member thus formed closely embrace one of the ribs 15 at the reduced portion 16 thereof. The width of said reduced portions 16, i. e. in the direction of the axis of the cup-shaped cage, is such that the beveled surfaces 17 cam said transverse member into clamping engagement with the flange ring 20, the outer ends of said hooks 25 engaging the flange ring 20 on its opposite side from the flange 19 and clamping said flange ring 20 therebetween. Packing or solder may be used to provide a fluid-tight joint between said flanges, if found desirable.

The bends 23 in the members 21 and 22 are of such size as to embrace the valve stem 9, as shown in Fig. 2, and form a guide therefor during the expansion and contraction of the thermostat. Although it is preferred to bend both of the strips 21 and 22 as shown, so that they are formed from duplicate blanks, said strips may be so designed that only one of them is bent, or their bends may be unequal, to embrace the valve stem. The width of said transverse member 21, 22 at or adjacent the guide portion 23 is also preferably so selected that the inner edge of said member 21, 22 constitutes a stop to limit the expansive movement of the thermostat by engagement with the movable end wall 3 thereof or by engagement with some suitable member carried by the valve stem or said movable wall.

A valve member of any suitable character is suitably mounted on the valve stem 9. In the form shown the valve disk 28 is provided with an interiorly threaded hub 29 by which it may be threaded onto the valve stem 9, and said valve disk is designed to be locked on said stem when properly positioned thereon by means of a cotter pin 30 passing through an aperture drilled in said hub and said stem.

The diameter of the cup-shaped cage 12 is such as to leave a substantial clearance between the ribs 15 and the periphery of the thermostat, so that there shall be no interference with the expansion and contraction of the thermostat. This also permits the thermostat to be introduced into said cup-shaped cage through the open end thereof. The outwardly extending flange 19 therefore requires the use of a valve disk 28 which is of appreciably greater diameter than the effective diameter of the corrugated tubular wall. It is sometimes desirable to use a valve disk

of materially smaller diameter, equal to or even smaller than the effective diameter of the corrugated tubular wall. To this end, a valve seat of smaller diameter than that of the open end of the cup must be provided and an embodiment of the invention providing for the use of a smaller valve disk is illustrated in Figs. 4 and 5.

In the form here shown the thermostat 1 with its threaded boss 4 on the stationary end wall and its valve stem 9 on the movable end wall, and the cup-shaped cage 12 apertured to provide a plurality of ribs 15, are of substantially the same construction as illustrated in Figs. 1, 2 and 3. In this embodiment of the invention, however, a separate valve seat ring is suitably secured within the open end of the cup-shaped cage 12 after the thermostat has been mounted therein. In the form shown, a ring 31 having an inwardly directed flange 32, which is machined or otherwise suitably formed so as to provide a valve seat 33, is suitably secured within the open mouth of the cup-shaped support or cage 12, as by solder 34. In order to predetermine the position of said ring 31 and prevent its movement into the cup beyond a definite distance, the ribs 15 are provided in any suitable way with means to limit the inward movement of said ring. In the form shown, one or more prick punch depressions 35 are made in each of the ribs 15, or a continuous groove might be formed transversely of said ribs, at such a position that the ring 31 is limited in its inward movement.

The valve disk shown in Fig. 4 is of the form disclosed and claimed in the application of Jean V. Giesler, William W. Carson, and Thomas R. Clark, Serial No. 145,343, filed October 30, 1926, and entitled Thermostatically controlled valve mechanism and is composed of a sheet metal disk 36 provided at its center with an interiorly threaded hub 37, which may be formed out of rod stock and suitably machined, said hub having an inwardly directed skirt 38 which may be secured in the disk 36 by peening or riveting over the inner extremity of said skirt. The transverse member 21, 22 for locking the flange ring between the flange 18 and their hook-shaped extremities 25 may be of substantially the same construction as heretofore described in conjunction with the embodiment of Figs. 1 to 3, or of any other suitable construction. Inasmuch as the flange 18 does not constitute a valve seat, however, it may be made of such size as to perform the function of the flange 20, shown in Fig. 1, in which event, the transverse member 21, 22 may serve no locking function but still perform the functions of a valve stem guide and a stop to limit the expansive movement of the thermostat.

In both of the embodiments so far described the flange 18 has been made integral

with the tubular wall of the cup-shaped cage 12, and any radially inwardly directed flange, such as 32 in Figs. 4 and 5, has been shown as secured to said cage. It is possible in some constructions to form the open end of the cup-shaped cage into an integral inwardly directed flange and then solder or otherwise suitably secure to the periphery of the cup-shaped cage an outwardly directed flange to serve the function of an attaching flange.

In assembling the parts, assuming that the thermostat 1 has first been formed and suitably charged and sealed, said thermostat is introduced through the open end of the cup-shaped cage 12 to project the threaded boss 4 through the aperture 14 in the bottom thereof. The thermostat is then fixedly clamped in position by threading the nut 5 onto said boss 4 until it clamps the bottom 13 of said cage fixedly between said nut and the stationary end wall 2. A flange ring 20, when used, having been applied over the outside of the cup-shaped cage 12 until it contacts the flange 18, the pair of members 21 and 22 are positioned on opposite sides of the stem 9, so that the curved portions 23 thereof embrace the valve stem 9 and the hook portions 25 thereof embrace the reduced portions 16 of a pair of opposed ribs 15, and said members 21 and 22 are then united in any suitable manner, such as heretofore described. As said members are thus forced into contact, the beveled faces 17 on the ribs 15 tend to cam the hook-shaped ends 25 of said members toward the outer end of the cup-shaped cage or support, forcing said hook-shaped ends against the flange ring 20 and rigidly uniting and clamping the latter between the flange 18 and said hook-shaped extremities. When the ring 31 is employed, said ring is introduced through the open end of the cup-shaped support and soldered or otherwise suitably secured in position. The valve disk may then be threaded onto valve stem 9 until it contacts the valve seat 19 or 32, and still further sufficiently to withdraw the tubular stop 11 from contact with stationary end wall 2, when the tubular stop is employed, whereupon said valve disk may be locked in position by means of the cotter pin 30, as heretofore described.

The thermostatically operated valve unit so formed may then be mounted in any suitable housing or on any suitable support in the cooling system of an internal combustion engine and the thermostat will expand and contract under changes of temperature to open and close the valve, the stationary end of the thermostat 2 being rigidly secured against displacement while the movements of the movable end of said thermostat are properly guided and limited.

As heretofore pointed out the thermostat may be of any suitable character and possessed of any suitable physical characteristics. It is preferably charged with a thermo-

sensitive fluid at a pressure below atmospheric, at normal temperature, so that at all temperatures below that at which the thermostat is designed to expand the interior pressure will be less than the exterior pressure. Therefore, if the thermostat leaks and the interior and exterior pressures become equalized, there is a tendency for the thermostat to expand and open the valve. The valve disk 5 may be made of any suitable size with relation to the effective diameter of the corrugated tubular wall, and provided with a leakage aperture if desired, and the size of the valve disk as compared with the effective area 10 of the corrugated wall may be so selected that the pressure of the circulating cooling medium tends to open the valve by reason of an unbalanced pressure thereon. This action may be availed of either alone or in conjunction with the charging of the thermostat at a pressure below atmosphere to effect the movement of the valve to open position upon failure of the thermostat. It is to be expressly understood, however, that any other suitable 15 character or construction of thermostat may be employed without departing from the present invention.

It will therefore be perceived that a simple thermostatically operated valve unit has been 20 provided which is composed of a relatively few simple parts which may be inexpensively manufactured and assembled. At the same time the unit is positive, accurate and efficient.

While the embodiments of the invention 25 illustrated on the drawings have been described with considerable particularity, it is to be expressly understood that the invention is not limited thereto as the same is capable of receiving a variety of mechanical expressions, some of which will now readily suggest 30 themselves to those skilled in the art, while changes may be made in the details of construction, arrangement and proportion of parts without departing from the spirit of 35 this invention. Reference is therefore to be had to the appended claims for a definition of the invention.

What is claimed is:

1. In a device of the character described, 40 in combination with a thermostat and a valve member operatively connected thereto, a cage for said thermostat provided at its open end with an outwardly directed flange constituting a valve seat for said valve member.

2. In a device of the character described, 45 in combination with a thermostat and a valve member operatively connected thereto, a cage for said thermostat having a closed bottom and provided at its mouth with a flange constituting a valve seat for said valve member, and means for securing said thermostat to the bottom of said cage.

3. In a device of the character described, 50 in combination with a thermostat and a valve member operatively connected thereto, a cage

for said thermostat having a closed bottom and provided with a radially directed flange constituting a valve seat for said valve member, the bottom of said cage being provided with an aperture, and a threaded boss on one end of said thermostat projecting through said aperture and secured to the bottom of said cage. 70

4. In a device of the character described, 75 in combination with a thermostat and a stem operatively connected thereto, a cage-like support for said thermostat including a plurality of longitudinally extending elements and a separate diametrically extending member attached to said elements inside of said cage-like support but adjacent the end thereof and forming a guide for the movement of said stem. 80

5. In a device of the character described, 85 in combination with a thermostat, a support for said thermostat including a plurality of longitudinally extending elements, and a member mounted on said elements for limiting the movement of said thermostat. 90

6. In a device of the character described, 95 in combination with a thermostat, a support for said thermostat including a plurality of longitudinally extending elements, a member mounted exteriorly on said support, and means mounted on said elements for locking 100 said member on said support. 105

7. In a device of the character described, 100 in combination with a thermostat and a stem operatively connected thereto, a support for said thermostat including a plurality of axially extending elements and a transverse member secured to said elements, said member being composed of a plurality of sections joined to embrace said stem and a plurality of said elements. 110

8. In a device of the character described, 115 in combination with a thermostat and a stem operatively connected thereto a support for said thermostat including a plurality of longitudinally extending elements, and a transverse member secured to said elements, said transverse member being composed of sections bent at their extremities to form clamping portions and bent intermediate their length to form a guide for said stem. 120

9. In a device of the character described, 125 in combination with a thermostat, a support for said thermostat including a plurality of longitudinally extending elements, a member mounted exteriorly on said support, and a transverse member secured to said elements and having hook-shaped extremities embracing said elements and clamping said member on said support. 130

10. In a device of the character described, 135 in combination with a thermostat, a support for said thermostat including a plurality of longitudinally extending elements, said elements being provided with one or more beveled faces, a member mounted exteriorly on 140

5 said support, and a transverse member for locking said first-named member in position, said transverse member being secured to said elements and cammed by the beveled faces thereon into locking relation with said first-named member.

11. In a device of the character described, in combination with a thermostat and a valve member operatively connected thereto, a cage 10 for said thermostat provided at its open end with a radially directed flange constituting a valve seat for said valve member and a second radially directed flange member secured to said cage adjacent its open end.

15. 12. In a device of the character described, in combination with a thermostat and a valve member operatively connected thereto, a cage for said thermostat provided at its open end with a radially directed flange constituting a 20 valve seat for said valve member, and a second radially directed flange member secured to said cage adjacent its open end, one of said flanges being integral with said cage.

13. In a device of the character described, 25 in combination with a thermostat and a valve member operatively connected thereto, a cage for said thermostat provided at its open end with a radially directed flange constituting a valve seat for said valve member, said cage including axially extending ribs, and a trans- 30 verse member secured to said ribs and forming a guide for the valve stem.

14. In a device of the character described, 35 in combination with a thermostat and a valve member operatively connected thereto, a cage for said thermostat provided at its open end with a radially directed flange constituting a valve seat for said valve member, said cage including axially extending ribs, and a trans- 40 verse member secured to said ribs and forming a stop to limit the movement of said thermostat.

15. In a device of the character described, 45 in combination with a thermostat and a valve member operatively connected thereto, a cage for said thermostat provided at its open end with a radially directed flange constituting a valve seat for said valve member, said cage including axially extending ribs, and a trans- 50 verse member formed of sections secured to said ribs and united to embrace the valve stem.

16. In a device of the character described, 55 in combination with a thermostat and a valve member operatively connected thereto, a cage for said thermostat provided at its open end with a radially directed flange constituting a valve seat for said valve member, said cage including axially extending ribs, and a trans- 60 verse member secured to said ribs and composed of sections having hook-shaped extremities whereby said sections may be clamped upon opposed ribs.

17. In a device of the character described, 65 in combination with a thermostat and a valve

member operatively connected thereto, a cage for said thermostat provided at its open end with a radially directed flange constituting a valve seat for said valve member, said cage including axially extending ribs having one or more beveled surfaces, a flange ring mounted on said cage in contact with said first named flange, and a transverse member secured to said ribs and cammed into locking engagement with said flange member by the action of said beveled surfaces on said transverse member.

18. In a device of the character described, in combination with a thermostat and a valve member operatively connected thereto, a cup-shaped cage for said thermostat, means for securing said thermostat to the bottom of said cage, and an integral outwardly directed flange at the mouth of said cage constituting a valve seat for said valve disk.

19. In a device of the character described, in combination with a thermostat, a cup-shaped cage for said thermostat, means for securing said thermostat to the bottom of said cage, and a sectional transverse member secured in said cage and constituting a stop for the thermostat.

20. In a device of the character described, in combination with a thermostat and a stem operatively connected thereto, a cup-shaped cage for said thermostat having an integral bottom, means for securing said thermostat to the bottom of said cage, and a sectional transverse member secured in said cage adjacent the open end thereof and constituting a guide for the movements of said stem.

In testimony whereof I have signed this specification.

WILLIAM W. CARSON, JR.
